REFRIGERATING APPARATUS

Wilford H. Teeter, Dayton, Ohio, assignor to General Motors Corporation, Dayton, Ohio, a corporation of Delaware

Application October 29, 1943, Serial No. 508,141

3 Claims. (Cl. 220—71)

This invention relates to refrigerating apparatus and particularly to ice cream storage refrigerators.

Conventional ice cream storage refrigerator cabinets, in stores were bulk ice cream is dispensed, have an opening or openings in the top wall of the cabinet providing access to a freezing chamber therein containing cans of bulk ice cream. During the act of placing a can or cans of ice cream in the freezing chamber of such cabinets, the cans must be manually lifted upwardly and swung over the top of the cabinet and thereafter lowered into the chamber. Such cans are ordinarily formed of metal and when filled with ice cream are quite heavy. Frequently, a can is not elevated high enough to clear the top of a cabinet and consequently the bottom portion or edge of such can strikes the top corner portion of the cabinet while endeavoring to swing the can over the cabinet. The exterior wall surfaces of ice cream storage refrigerators are usually covered with metal panels or the like, and when a can of ice cream strikes the corner portion of a cabinet the metal top wall or side wall thereof or both metal walls are bent and damaged. If the metal exterior cabinet walls are painted or coated with porcelain enamel, the paint or enamel is chipped off and these walls soon rust and become deteriorated. It is necessary to frequently replace such damaged metal cabinet walls in order to maintain a sanitary condition and neat appearance of ice cream storage cabinets in stores or the like. This replacement of the cabinet metal walls is an expensive practice as well as being a difficult task.

An object of my invention is to provide an improved refrigerator cabinet construction which will reduce to a minimum the necessity of replacing damaged exterior walls of ice cream storage refrigerators.

Another object of my invention is to provide an improved corner structure particularly for ice cream cabinets, which structure can be repeatedly struck by heavy objects without damaging same.

A further object of my invention is to provide an exterior wall surface for a corner structure of an ice cream storage cabinet which will prevent other parts of the cabinet walls from being damaged when the corner structure is struck by heavy objects.

A still further and more specific object of my invention is to provide an ice cream storage cabinet with corner walls about the top there-

of formed of rubber or the like resilient material to prevent these corners from being damaged upon being struck by cans of ice cream.

Further objects and advantages of the present invention will be apparent from the following description, reference being had to the accompanying drawings, wherein a preferred form of the present invention is clearly shown.

In the drawings:

10 Fig. 1 is a perspective view of a refrigerator cabinet showing a refrigerating system diagrammatically associated therewith;

15 Fig. 2 is an enlarged fragmentary sectional view of a top corner of the cabinet and is taken on the line 2—2 of Fig. 1;

Fig. 3 is an enlarged view of a side portion of the cabinet with the corner strip or wall broken away;

20 Fig. 4 is an enlarged sectional view taken on the line 4—4 of Fig. 1 of a top three-way corner of the cabinet; and

Fig. 5 is an enlarged fragmentary perspective view of the top three-way corner of the cabinet showing the mounting for a metal corner member.

25 Referring to the drawings, for illustrating the present invention, I have shown in Fig. 1 there-of a refrigerating apparatus of the ice cream storage type wherein the rectangularly-shaped 30 refrigerator cabinet is designated by the reference numeral 10. Cabinet 10 includes vertical metal exterior shells, walls or finish panels 11, a top metal exterior member 12 and an interior metal lining member 14 forming walls of a food storage chamber 15 (see Fig. 2) within the cabinet. The cabinet 10 has an opening or openings 35 in its top wall providing access to the chamber 15. A door or doors 13 normally close the chamber access openings. The frame of the cabinet 40 comprises a relatively heavy metal member 16 extending around the top portion of cabinet 10 and butt welded to corner posts (not shown). This frame supports a relatively heavy sub-top member 17 which may be secured thereto by 45 bolts or the like 18 (see Fig. 2). The exterior finish top panel 12 rests upon the sub-top member 17 and has its outer edge portions 19 bent down and secured to the sub-top member by screws or bolts 21. Any suitable insulating material 22 may be disposed between the panels 11, sub-top 17 and the liner 14 to effectively insulate the chamber 15. A metal channel member 25, having leg portions 26 and 27 spaced from member 16 for a purpose to be presently described, 50 is welded upon the frame member 16 and is co-

extensive therewith at the top corners of cabinet 10. The leg portion 27 of corner channel member 25 has cut-out portions 28 (see Fig. 3) spaced about twelve inches apart along the sides of cabinet 10 to provide openings whereby the screws 21 may be fastened in place.

Before proceeding with further description of the cabinet structure, I wish to set forth that a closed refrigerating system is associated with the cabinet 10. This system includes an evaporator comprising a conduit 31 wrapped around and secured to the liner 14 of chamber 15 for cooling the interior of the chamber. Evaporator 31 is connected with a refrigerant translating and circulating unit mounted on a base 32. This unit comprises a sealed motor-compressor 33, a condenser 34 and a snap acting switch 35. Evaporated refrigerant is withdrawn from evaporator 31, by compressor 33, through conduit 36. Vaporized refrigerant entering the compressor 33 is compressed and circulated, under pressure, through a conduit 37, into the condenser 34. The compressed refrigerant is cooled and liquefied in condenser 34 and is directed through a conduit 38 into the evaporator 31 under the control of a restrictor or expansion valve 39. A closed thermostatic system including a bulb 41 mounted upon liner 14, conduit 42 and a bellows 43 actuates switch 35 to control operation of the motor of the motor-compressor 33, in accordance with the temperature produced by evaporator 31, to maintain the interior of chamber 15 at a constant low temperature as is conventional in the art.

In order to provide cabinet 10 with an exterior corner and particularly a top corner which will not be damaged under the conditions hereinbefore described, a resilient element 51, formed of rubber, synthetic rubber, or a plastic material, is located at the top corners of the cabinet. In making this element of rubber the rubber is formed into a long one-piece strip by conventional extruding methods and has a predetermined cross-sectional contour. This cross-sectional contour of element 51 includes a relatively thick main body cushioning portion 52 having a round hole 53 provided centrally thereof and extensive therewith (see Fig. 2). An integral web or bead 54 formed on element 51 interlocks with or fits under the leg portion 27 of channel member 25 to hold one edge of element 51 on cabinet 10 in abutting relation to the turned down edge portion 19 of top panel 12. Another integral web or bead 55 formed on element 51 interlocks with or fits under the leg portion 26 of channel member 25 and over the top edge of side panel 11 to secure the lower portion of element 51 to the cabinet 10. This abutment of web or bead 54 with the edge portion 19 of panel 12 in addition to concealing the edge of this panel is of such tightness that it insures against entrance of water or other foreign matter to a point beneath the member 51 to thereby prevent rusting and/or corrosion of metal parts inwardly of the corner wall surface. An integral flexible lip 56 extends outwardly and depends from the lower portion of element 51 and overlaps the top edge portion of the cabinet side panel 11 so as to conceal this edge and the point or points of weld of panel 11 to frame member 16 and to also protect the top portion of the panel or wall 11. The removable interlocking of the webs or beads 54 and 55 of element 51 to channel member 25 holds the main body portion 52 of the element in abutting relation with the cabinet top corner structure to form the exterior wall surface of these

corners. The hole 53 in element 51 adds resiliency to the main body portion 52 thereof so as to increase its cushioning effect when the wall is struck by a can of ice cream or the like. At the corners where the cabinet top, end and adjacent side walls meet, a slot 58 is cut in the resilient element 51 (see Fig. 5) so that the element may be bent, stretched or extended around these corners of the cabinet 10 without buckling. At each of these three-way corners of cabinet 10, the corner portion of frame member 16 has a metal piece 59 welded thereto (see Fig. 4). The metal piece 59 is provided with a tapped hole at 61 (see Fig. 5) to receive a screw 62 which holds a corner metal trim member 63 in place. The metal corner trim 63, while concealing the slot 58 in element 51, also adds to the neat appearance of the cabinet.

In assembling the strip of corner wall-forming element 51 to cabinet 10, its linear bead or web portion 55 is first pushed into the space between the leg 26 of channel member 25, frame 16 and the top edge of side panel 11 to lock the one edge of the element upon the cabinet. Thereafter, the element 51 is stretched to permit its linear bead or web portion 54 to be pushed or forced into the space between the leg 27 of member 25, frame 16 and the downwardly bent edge portion of the cabinet top 12 to lock the other edge of the element upon the cabinet. A soap solution or the like may be applied to element 51 to facilitate slipping of the rubber beads or webs into place. Each metal corner trim member 63 is located in place by a screw 62 threaded into the tapped hole 61 of metal piece 59, after the strip 51 is bent around the three-way corners of the cabinet and secured thereto as described.

From the foregoing, it will be seen that I have provided an improved refrigerator cabinet corner wall structure and particularly a top corner wall structure for ice cream storage or the like cabinets. My invention provides an exterior wall for top corners of ice cream storage or the like cabinets which is resilient and which will not be marred or damaged upon being struck by heavy objects and also affords protection to the metal cabinet walls immediately adjacent such corners. By virtue of the resiliency of the exterior corner wall, it can be quickly and easily assembled in place.

50 While the form of embodiment of the invention as herein disclosed, constitutes a preferred form, it is to be understood that other forms might be adopted, as may come within the scope of the claims which follow.

55 What is claimed is as follows:

1. A refrigerator cabinet having a bottom wall, a top wall and an upright wall structure forming a food storage chamber within said cabinet, means in said cabinet top wall providing an access opening for said chamber, movable means normally closing said chamber access opening, a sheet member disposed over said cabinet top wall, a sheet member disposed over said cabinet upright wall structure, the juncture of said top wall with said upright wall structure providing an exposed corner extending horizontally around the top of said cabinet, said first and said second named sheet members having their edges at said corner terminating short thereof and in spaced apart relation to one another, and a non-metallic resilient element interposed between and concealing the spaced apart edges of said members and being secured to said cabinet to form the exterior wall of said corner.

70 2. A refrigerator cabinet having a bottom wall,

a top wall and an upright wall structure forming a food storage chamber within said cabinet, means in said cabinet top wall providing an access opening for said chamber, movable means normally closing said chamber access opening, a sheet member disposed over said cabinet top wall, a sheet member disposed over said cabinet upright wall structure, the juncture of said top wall with said upright wall structure providing an exposed corner extending horizontally around the top of said cabinet, said first and said second named sheet members having their edges at said corner terminating short thereof and in spaced apart relation to one another, a non-metallic element interposed between and concealing the spaced apart edges of said members and being secured to said cabinet, said element having a relatively thick resilient portion forming the exterior wall of said corner, and said element also having a flexible lip extending away from said thick portion thereof and overlapping a portion of said sheet member disposed over said upright wall structure adjacent its edge.

3. A refrigerator cabinet having a bottom wall, a top wall and an upright wall structure forming a food storage chamber within said cabinet, means in said cabinet top wall providing an access opening for said chamber, movable means normally closing said chamber access opening, a sheet member disposed over said cabinet top wall, a sheet member disposed over said cabinet upright wall structure, the juncture of said top wall with said upright wall structure providing an exposed corner extending horizontally around the top of said cabinet, said first and said second named sheet members having their edges at said corner terminating short thereof and in spaced apart relation to one another, a non-metallic element interposed between and concealing the spaced apart edges of said members and being secured to said cabinet, and said element having a relatively thick resilient portion forming the exterior wall of said corner.

WILFORD H. TEETER.
